UNITED STATES PATENT OFFICE.

JAMES VERNON CARTER, OF ELLIOTT, SOUTH CAROLINA.

DISTRIBUTER.

1,095,380.

Specification of Letters Patent.

Patented May 5, 1914.

Application filed June 25, 1913. Serial No. 775,763.

To all whom it may concern:

Be it known that I, JAMES VERNON CARTER, a citizen of the United States, residing at Elliott, in the county of Lee and State 5 of South Carolina, have invented certain new and useful Improvements in Distributers, of which the following is a specification, reference being had to the accompanying drawing.

10 My invention relates to distributers for fertilizer and the like, and has for its objects a machine easy to manufacture; with a large hopper having its weight over the draft wheel, and a positive feed device and 15 lump breaker; and means whereby it is possible to use the machine for delivery to the side of the central line of travel, if desired.

There are other objects and advantages hereinafter described and claimed.

20 Figure 1 is a view of the right hand side of the distributer, looking at same from a point behind. Fig. 2, the left hand, or driving side; Fig. 3, a view looking down into the hopper. Fig. 4 is a plan view of 25 the feed wheel and lump breaker. Fig. 5 shows the adjustable outlet in plan view. Fig. 6 shows the adjustable outlet in side elevation.

Like figures of reference denote the same 30 parts wherever they are shown.

1 denotes a hopper of any suitable construction supported on a frame 2, to which are secured the forwardly projecting supports 3 and 4 for the clevis 5 by which the 35 distributer is drawn along. The draft wheel 6 is suitably supported in bearings 7 and 8. The hopper extends above the wheel 6 for the purpose of carrying a surplus supply of fertilizer, and to distribute the 40 weight, which prevents the draft wheel slipping. The bottom portion 9 of the hopper slopes downward toward the outlet which is positioned below the feed wheel 10.

Journaled in bearings 12, suitably mounted 45 on either side of the hopper 1, and extending across the hopper immediately above the outlet thereof, is a shaft 11 which has firmly fixed thereon the aforesaid feed-wheel 10. One end of said shaft 11 extends 50 outwardly beyond its bearing 12 and has securely mounted thereon a sprocket wheel 13. Sprocket 13 is adapted to be driven by a sprocket 15, mounted on the axle of draft wheel 6, through the medium of a chain 14 55 which passes over said sprocket wheels in

the usual manner. Feed wheel 10 carries two bent members 33 and 34 which revolve with it and crush any lumps that may be in the fertilizer.

18, 19, and 20 are plow points removably 60 fixed to standards which are detachably secured to the frame 2 of the machine. Normally these may be fixed at an angle to the path of travel of the machine, as shown in Fig. 1 so that in operation 18 will open the furrow, spout 21 will deliver the fertilizer to the open furrow, and 19 and 20 will cover the furrow.

If a center delivery machine is desired, the angularly disposed spout 21, which is 70 detachably fastened below the discharge port of the hopper, is removed, and the standard of plow share 18 is disconnected from the point indicated at 23, Fig. 1, and connected at the point indicated by 24, thus 75 giving the arrangement shown in Fig. 2. By this arrangement the fertilizer is delivered in front of the plow 19 which, in cutting its furrow, throws up the soil and fertilizer and to some extent covers the latter, and plows 18 and 20 being positioned rearwardly and to either side of plow 19, complete the covering of the fertilizer with the soil.

To guide the machine, handles 25 and 26 80 are attached in any suitable manner.

The adjustable outlet consists of a metal plate 27 forming the bottom portion of the hopper behind wheel 6. This plate has a slot 28 the area of which is varied by the 90 slide 29. A handle 30 projects rearwardly from 29, and is provided with a number of holes and a pin 31, which strikes against piece 32 thereby limiting the opening of the slide. The upturned end 38 of the slide is 95 provided for preventing side motion and prevents fertilizer from packing between the feed wheel and outlet. The stop pin 32 enables the slide 29 to be closed at will, and opened to exactly the same capacity without looking for any marks, notches or other indications.

The feed wheel shown as a whole at 10, Figs. 3 and 4, is composed of the lump breaking members 33 and 34 which are simply round iron rods flattened for a portion of their length, threaded and screwed into the hub flange 35. The distributing fingers 36 and 37 are rods radially secured to flange 35, and bent outwardly in alternately oppo- 110

site directions. Such construction is not only cheap, but is superior to a cast wheel all one piece, as it is not so easily broken.

I claim—

- 5 1. In a distributor, a hopper and a feed wheel in said hopper comprising a hub carrying radial spokes flattened for a portion of their length and bent laterally in alternately opposite directions.
- 10 2. In a distributor, a feed wheel comprising a hub carrying radial spokes flattened for a portion of their length and bent laterally in alternately opposite directions, and a pair of lateral arms a portion of which are bent in a plane with the path of travel of said spokes, substantially as described.
- 15 3. In a distributor, a feed wheel comprising a hub carrying radial spokes, the outer ends of which are inclined in alternately opposite lateral directions, and means carried by said hub independent of said spokes, for stirring, substantially as described.
- 20 4. In a distributor, a hopper, a metal plate forming the bottom of said hopper and having a longitudinal centrally located aperture, a slide carried by said plate and

adjustably secured thereto for regulating the size of the aperture therein, a feed wheel comprising a hub having radial spokes with portions alternately bent laterally in opposite directions, a draft wheel, means for driving said feed wheel from said draft wheel, a framework supporting said hopper and a plurality of plows attached to said framework, one of said plows being adapted for attachment at two places on said framework, substantially as described.

5. In a distributor, a feed wheel comprising a hub carrying radial spokes, the outer ends of which are inclined in alternately opposite lateral directions, means carried by said hub, independent of said spokes, for stirring, a frame work, and a plurality of plows attached to said frame work, one of said plows being attached at one or more places thereon.

In testimony whereof I hereunto affix my signature in the presence of two witnesses.

JAMES VERNON CARTER.
